[57] CLAIM

The ornamental design for an ear-microphone for cellular phones, as shown and described.

DESCRIPTION

FIG. 1 is the perspective view thereof.

FIG. 2 is the front elevational view thereof.

FIG. 3 is the rear elevational view thereof.

FIG. 4 is the left side elevational view thereof (the right side elevational view thereof is a mirror image).

FIG. 5 is the top plan view thereof; and,

FIG. 6 is the bottom plan view thereof.

A portion of the article has been shown broken away throughout the views to indicate indeterminate length.
